assignors to Dixie Wax Paper Company, Inc.,
Dallas, Tex., a corporation of Texas

Application June 2, 1939, Serial No. 276,956

15 Claims.

(Cl. 93—6)

This invention relates to new and useful improvements in methods of and means for sealing packages.

One object of the invention is to provide an improved method which is particularly adapted for use in sealing packages constructed of wax paper, such as the bags in which food products are packaged.

An important object of the invention is to provide an improved method for sealing packages, wherein the open end of each package is folded so as to close the package, after which said folded end is sealed to permanently close said package, the folding and sealing being done in a continuous operation.

Another object of the invention is to provide an improved method for sealing packages after said packages have been filled with a food, or other product, without damaging or injuring the contents of said packages.

A further object of the invention is to provide an improved method of closing and sealing packages made of waxed material, wherein the packages are carried by a moving conveyor and the open ends of said packages are successively folded, heated, crimped and sealed, whereby each package is automatically closed and sealed in a minimum length of time and without any manual labor.

Still another object of the invention is to provide an improved apparatus for sealing packages which includes a movable conveyor for receiving the packages to be sealed, said conveyor being arranged to move each package into a folding assembly which folds the package material at the open end of said package upon itself to close said open end, after which said conveyor carries the package successively through heating, crimping and pressure assemblies to seal said package in such closed position.

A particular object of the invention is to provide an improved folding assembly for package sealing apparatus which is constructed so as to first fold the material at a right angle and then downwardly upon itself to close the open end of the package, whereby the necessity of manually folding said material is obviated.

Still another object of the invention is to provide an improved apparatus, of the character described, wherein the various retaining and guide rollers and pulleys which guide the packages in their movement, are yieldably mounted, whereby a proper pressure, sufficient to maintain the packages in proper position at all times, is had.

A further object of the invention is to provide an improved apparatus, of the character described, which is simple in its construction and economical in manufacture, said apparatus including a minimum number of parts which require little or no adjustment, whereby the efficiency of the apparatus is increased.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a plan view of an apparatus, constructed in accordance with the invention, for carrying out the improved method,

Figure 2 is a longitudinal, vertical, sectional view, taken on the line 2—2 of Figure 1,

Figure 3 is a rear elevation of the upper portion of the apparatus,

Figure 4 is a perspective view of the supporting frame and table,

Figure 5 is an enlarged longitudinal, vertical, sectional view, taken on the line 5—5 of Figure 1,

Figure 6 is a transverse, vertical, sectional view, taken on the line 6—6 of Figure 5,

Figure 7 is a transverse, vertical, sectional view, taken on the line 7—7 of Figure 5,

Figure 8 is a transverse, vertical, sectional view, taken on the line 8—8 of Figure 5,

Figure 9 is a transverse, vertical, sectional view, taken on the line 9—9 of Figure 5,

Figure 10 is an enlarged isometric view of the folding assembly block,

Figure 11 is an isometric view of one of the bearing supports for the roller shaft,

Figure 12 is an isometric view of one of the crimping rollers,

Figure 13 is a vertical, sectional view taken on the line 13—13 of Figure 1, and

Figure 14 is a schematic view, illustrating the various steps of the improved method, whereby the package is folded and sealed.

In the drawings, the numeral 10 designates a flat table or support which is provided with vertical standards or legs 11 (Figure 4). A supporting framework 13 is secured to the legs of the table and an elongate platform or deck 14 is secured to the framework 13 by inclined braces 15.

As is clearly shown in Figure 8, the deck 14 is disposed in a plane above the top of the table 10. The length of the deck 14 is greater than the length of the table 10, whereby the ends of said

deck extend beyond the transverse edges of the table.

A bearing support 16 is mounted on the longitudinal bar 13a of the framework 13, being disposed at one end of said bar. A transversely extending shaft 17 has one end journaled in the bearing 16 while its opposite end is mounted in a similar bearing 16', which latter bearing is mounted on short supporting bars 13' which form a part of the framework 13. The shaft 17 extends beneath one end of the longitudinal deck 14 and is provided with a pair of sprockets 18 which are secured one on each side of said deck, as is clearly shown in Figure 1. A bearing bracket 16a, similar to the bearing 16, is mounted on the opposite end of the longitudinal frame bar 13a. One end of a transverse shaft 17a is journaled in the bearing 16a, while the opposite end of said shaft is secured in a bearing bracket 16b, which bracket is secured to the top of the table 10. As is clearly shown in Figure 1, the shaft 17a extends beneath the end of the deck 14 and is provided with a pair of sprockets 19, which are disposed one at each longitudinal edge of said deck. The sprockets 19 on the shaft 17a are alined with the sprockets 18 on the shaft 17, whereby a pair of endless chains 20 may pass around said sprockets. Manifestly, when one of the shafts is rotated, the chains travel over the sprockets. For rotating the shaft 17, said shaft is provided with a drive gear 21 which is secured on said shaft beyond the bearing support 16'. An endless drive chain 22 is utilized to rotate the gear 21, as will be hereinafter explained.

The elongated deck 14 is adapted to receive the packages which are to be closed and sealed and in order to move said packages longitudinally of said deck a plurality of angle bars 23 are provided. Each bar has one end secured by means of an angle member 24 to one of the chains 20, as is clearly shown in Figure 8. The other end of the angle bar 23 is secured to the other chain by a similar member. By observing Figure 1, it will be seen that the bars 23 are spaced throughout the length of the chains 20 and, when the shaft 17 is rotated, the angle bars 23 are moved longitudinally of the deck 14. Since the chains are located, one on each side of the deck 14, the bars 23 span and overlie the deck. Also, the deck serves as a support for said bars which move therealong as the sprockets 18 and 19 are rotated. The spacing between the bars 23 is, of course, subject to variation, but it is preferable that this spacing be such that one package can be placed or received between adjacent bars.

It is possible to seal various types of containers or packages but the packages shown in the drawing have been illustrated as bags or sacks A, which receive food products, such as potato chips, corn chips and the like. The containers may be filled in any suitable manner and the filled containers placed on the left side in Figure 1 of the deck 14. As the conveyor, which is formed by the chains 20 and the bars 23, moves longitudinally of the deck, one of the bars will strike the package A, which is indicated in dotted lines in this figure. Obviously, as the conveyor moves longitudinally of the deck, the package A will be carried along said deck by said conveyor. For properly positioning each package on the deck, a guide member or plate 25 is provided. This guide plate extends vertically and is secured to an upright 26, which upright is mounted on one of the bars 13' of the frame- 75

work 13. The vertical face of the plate 25 extends parallel to the longitudinal edge of the deck 14 and when the package A is placed on said deck between two of the bars 23 of the conveyor, the open end of said container is placed against this vertical face. The guide plate 25 is positioned so that the open end of the package is properly positioned to pass through the succeeding element of the apparatus, as will be hereinafter explained. It is pointed out that the guide plate 25 is spaced from the longitudinal edge of the deck (Figure 1), whereby the open end of the package A extends beyond the longitudinal edge of said deck.

15 For clamping the extended end of each package, as said package moves longitudinally of the deck, a pair of clamping belts 27 and 28 are provided (Figure 2). The clamping belt 27 passes over a pulley 29, which pulley is mounted on a shaft 30 which is secured or carried by the upright 26. The belt also passes around a pulley 31, which is mounted on a shaft 32. The shaft 32 is journaled in a suitable bearing 33, which bearing is mounted on the table 10 (Figure 1). The belt 27 also engages a plurality of intermediate pulleys, which will be hereinafter explained. The lower belt 28 passes over a pulley 35, which is mounted on the shaft 17 of the conveyor. This belt also passes over a second pulley 36, which is spaced from the pulley 35 and which is mounted immediately below the pulley 31 of the upper belt 27. The pulley 36 is mounted on a shaft 37, which shaft is connected through suitable gears with the shaft 32 on which the pulley 31 is mounted. The belt 28 also passes over a plurality of intermediate pulleys, as will be explained, and is arranged to extend contiguous to the upper belt 27 throughout a goodly portion of its length. With the above arrangement, when the drive shaft 17 of the conveyor is rotated, the pulley 35 is also rotated, whereby the lower belt 28 is caused to move over its pulley. Since the pulleys 36 and 31 are geared together, the upper belt 27 will also be caused to travel over its pulley. As is clearly shown in Figure 2, the lower belt 28 is longer than the upper belt 27, whereby when a package A is placed on the deck, with its open end engaging the guide plate 25, said open end of the package overlies the belt 28. As the conveyor moves longitudinally of the deck, the package is carried to the right in Figures 1 and 2, and the open or extended end of said package is moved between the belts 27 and 28 so as to be firmly clamped therebetween. It is noted that the belts 27 and 28 are cylindrical in cross-section, as is clearly shown in Figures 6 to 8.

For guiding the belts 27 and 28 into engagement with each other, so that the extended end of the package A may be clamped therebetween, a pair of clamping rollers 38 and 39 are provided. These rollers are clearly shown in Figures 5 and 6 and the lowermost roller is mounted on a shaft 40, which is journaled in an upright support 41. The upper roller 39, which is in vertical alinement with the lower roller 38, is mounted on a shaft 43, which shaft extends through a block 44. This block is slidable vertically within a slot 45 formed in the upper end of the support 41. A plate 46 closes the upper end of the slot 45 and a coiled spring 47 is confined between the upper end of the supporting block 44 and said plate, whereby said spring constantly urges the shaft 43 and roller 39 downwardly into engagement with the lower roller 38. The shafts 40 and 43 are extended be-

yond the upright support 41 and are provided with meshing gears 48, whereby said shafts and the rollers are simultaneously rotated at the same speed. Each roller is formed with a groove 49 at the outer edge portion of its periphery and said groove forms a pulley wheel through which the belts 27 and 28 are guided.

Adjacent the rollers 38 and 39 and mounted in a similar manner on an upright support 41a are a pair of rollers 50 and 51, the lower roller being mounted on a shaft 50a and being spaced a fixed distance from the support. The upper roller 51 has its shaft 51a mounted within a block, similar to the block 44, whereby the upper roller is constantly urged downwardly into engagement with the lower roller. The rollers 50 and 51 have their shafts connected by meshing gears 52 so as to rotate the rollers simultaneously and at the same speed. The rollers 50 and 51 are also provided with grooves 53 at the outer portion of their periphery, whereby guide pulleys for the belts 27 and 28 are provided.

As explained, the rollers 38 and 39 are exactly alike in construction, but this is not true of the rollers 50 and 51 for, as is clearly shown in Figure 7, the lower roller 50 is formed with an annular flange 54. This flange is formed at the inner side of the roller 50 and is preferably made integral therewith. As illustrated, the flange extends outwardly from the periphery of the roller 50 and abuts the inner face of the upper roller 51. The purpose of this flange is to fold the material of which the package is constructed upwardly at substantially a right angle, as will be hereinafter explained.

Immediately behind the rollers 38, 39, 50 and 51 is a curved guide shoe 55. This guide shoe has a horizontal portion which is adjacent the end of the guide plate 25 (Figure 1) and said shoe is bent upon itself so that the remainder thereof is curved to a vertical position, the vertical portion being immediately behind the peripheral edge of the rollers 50 and 51. The shoe is welded or otherwise secured to the support 41 (Figure 6). The purpose of this shoe is to support the open end of the package passing between the rollers 38 and 39 and also to guide the end of said package into the folding assembly block B, which is immediately adjacent the rollers 50 and 51 and which will now be described in detail.

The block B (Figures 9 and 10) is substantially T-shaped in cross-section and is supported upon a channel member 56 which is secured to the top of the table 10. The upper end of the block is formed with a longitudinally extending groove 57 which extends throughout the length of the block. The end of the block, which is adjacent the rollers 50 and 51, is cut away as shown at 58. The groove 57 is flared upwardly to meet the cutaway portion whereby the upper portion of the groove is inclined as shown at 59. An elongate bar or finger 60 is disposed within the enlarged end of the groove 57 and is supported by an upright arm 61 which has its upper end secured to a boss 62 which is formed integral with the top of the block. The finger, as is clearly shown in Figures 5 and 10, is spaced from the bottom of the groove a sufficient distance to permit the extended portion of the bag, which is travelling along the conveyor between the belts 27 and 28, to pass therebeneath. In addition to the boss 62, the top of the block B is formed with a pair of other bosses 62' and 62a, these bosses being spaced from each other and from the first mentioned boss 62.

A trio of guide pulleys 63 are mounted on shafts 64, which shafts extend through the bosses 62, 62' and 62a. The shafts are journaled within the bosses, whereby the pulleys 63 are freely rotatable. The pulleys 63 are in the same plane as the pulleys or grooves 49 and 53 on the rollers 38 and 51, whereby the upper belt 27 may ride in the grooves thereof.

A lower trio of pulleys 65 are mounted immediately below the pulleys 63 and each pulley 65 is secured on a shaft 66. Each shaft is journaled within a flanged bearing support 67 (Figure 11). Each bearing support is slidable vertically within a vertical slot 68 formed in the block B and a coiled spring 69 engages the underside of said support. The lower end of each spring is mounted within a recess 70 formed in the top of the channel member 56 and the coiled springs 69 exert their pressure to constantly urge the bearing supports 67 upwardly, whereby the pulleys 65 are urged upwardly toward the upper pulleys 63. The pulleys 65 are in the same vertical plane as the pulleys 49 and 53 on the rollers 38 and 50, whereby the lower belt 28 may pass thereover. With the above arrangement, the pulleys 65 are yieldable, whereby a clamping engagement of the extended end of the package A by the belts 27 and 28 is assured.

The rear portion of the block B is formed with recesses 71, which recesses receive a pair of electrical heating elements 72. When the heating elements are operated, they serve to heat the upper portion of the block, whereby the end of the package, which is travelling through the groove 57, will be heated, as will be more fully explained.

From the above, it will be seen that a package placed on the deck 14 will be carried successively through the rollers 38 and 39, then through the rollers 50 and 51 and then through the groove 57 of the folding assembly block B. After passing from the block B, the package will be carried between a pair of crimping rollers 74. The periphery of each crimping roller is formed with a plurality of transverse and peripheral grooves or ridges 75, whereby that portion of the bag or package A passing between said rollers will be crimped. The mounting of the crimping rollers is clearly shown in Figure 5, the lower roller being fixed on a shaft 75' which is mounted within an upright support 76 extending upwardly from the table 10. The upper roller is mounted on a shaft 77, which shaft has its end journaled in a block 78. The block is formed with a slot 79 and is slidable on an upright bar 80, as is clearly shown in Figure 3. The bar 80 has its upper end bent at substantially a right angle and an adjusting screw 81 is threaded through the horizontally extending portion of the bar. The lower end of the adjusting screw is secured to the block 78 and it is manifest that when said screw is rotated, the block 78 will be lowered or raised on the supporting bar 80. Since the upper roller 74 is carried by the block 78, an adjustment of said block vertically will adjust the upper roller relative to the lower roller 74. In this manner, the pressure of the rollers against each other may be readily adjusted. The shafts 75' and 77 are connected by meshing gears 75a and the outer portion of the peripheries of the rollers are grooved to receive the belts 27 and 28.

After passing between the crimping rollers 74, the package A is conveyed to a pair of pressure belts 82 and 83. The upper belt 82 encircles a roller 84, which roller is made integral with the

pulley 31 over which the belt 27 passes. This upper belt also passes over a roller 85, which is mounted on a shaft 86 supported in an upright 87. The lower belt 83 passes over a roller 88, which is made integral with the pulley 36 over which the belt 28 passes. The flat pressure belt 83 also encircles a roller 89, which is mounted on a shaft 90, also supported in the upright 87. The pressure belts 82 and 83 are flat, and are held in close contact with each other by means of a flat spring member 90', which is shown in Figure 13. The spring member 90' overlies the upper belt 82 and has one end secured to a lateral deck or supporting bar 91, which bar is carried by posts 92 extending upwardly from the table 10. This arrangement assures that the belts 82 and 83 will travel in close proximity to each other, whereby when the end of the package A is passed therebetween, the belts will exert a pressure against said package.

Any suitable gearing or mechanism may be utilized to drive the conveyor and the various rollers and pulleys but, as illustrated, an electrical motor 95 is provided. This motor is mounted on the table 10 and has connection through a worm and gear 96 with the shaft 37 on which the roller 88 and pulley 36 are mounted. Therefore, when the motor is operating, the shaft 37 is rotated to drive the belts 28 and 83. Since the shaft of the roller 88 is geared to the shaft 32 of the roller 84 and pulley 31, it will be obvious that a rotation of the shaft 37 will impart a similar rotation to the shaft 32 to drive the belts 27 and 82.

For driving the shaft 75' of the lower crimping roller 74, a chain drive 97 connects the shaft 37 with the shaft 75'. Therefore, when the motor is operating, the rotation of the shaft 37 imparts a rotation to the crimping rollers 74. A chain drive 98 connects the shaft 75' with the shaft 50a of the roller 50. Since the roller 50 is geared to the roller 51 through the intermeshing gears 52, these rollers will operate or revolve at the same speed. A chain drive 99 connects the shaft 50a with the shaft 40 of the roller 38, whereby a simultaneous rotation of the rollers 38 and 39 may be obtained. The chain 22 which passes over the sprocket 21 on the conveyor drive shaft 17, as has been explained, passes over a similar sprocket 21a which is provided on the shaft 40 and, thus, it will be seen that the various chain drives will operate the conveyor, rollers, pulleys and belts at the same rate of speed. Of course, if desired, another method of driving the various parts may be employed.

In the operation of the device and apparatus, reference is made to Figure 14 which schematically shows the various steps of the method as performed by the apparatus hereinbefore described. The package A, which has been shown as a bag or sack, which is constructed of a waxed paper, is first filled with the product and is then placed on the deck 14 between two of the transverse conveyor bars 23. When in position on the deck, the open end of the sack abuts the vertical surface of the guide bar or plate 25, as indicated by the dotted lines in Figure 1. In such position, the inner portion of the bag or package A overlies the lower circular belt 28. Since the conveyor chains 20 are constantly operating, it will be manifest that the bar 23 will strike the side of the package A and move the same toward the right in Figures 1 and 2. As the conveyor moves the package A inwardly, said package is moved between the belts 27 and 28 which meet at the

rollers 38 and 39 (Figure 2). The belts 27 and 28 merely serve to clamp and hold the package in its proper position throughout the operations which are performed upon the bag in closing and sealing the open end.

Referring again to Figure 14, it will be seen that the bag is first moved opposite the rollers 38 and 39, whereby the end portion of said bag moves therebetween. These rollers serve to flatten 10 the end portion of the bag and clamp the same while the edge of said bag overlies or rides on the horizontal portion of the guide shoe 55 which is located immediately behind the rollers 38 and 39. As movement of the bag continues, 15 the outer or open end of the bag strikes the curved portion of the shoe 55 and, due to the curvature of said shoe, the outer end of the bag is turned upwardly. As said end is turned upwardly, the bag moves between the next pair of rollers 50 and 51.

As has been explained, the lower roller 50 of this pair is provided with the annular flange 54 and, manifestly, since the inner end of the bag is turned upwardly, the bag or package A will pass 20 between the rollers 50 and 51 in the manner shown in Figure 14. The flange 54 of the lower roller 50 will serve to crease the outer portion of the bag, bending the extreme outer edge thereof at substantially a right angle to the remainder of the bag.

After the outer portion of the bag has been turned upwardly by means of the rollers 50 and 51, said outer portion enters the enlarged portion of the groove 57 in the block B. As it enters said groove, the upturned portion of the bag or package abuts the inner vertical wall of said groove and passes therewith. The remainder of the extended portion of the bag passes beneath the elongate bar or finger 60, as 30 indicated in Figure 14. Continued movement of the bag causes the upturned portion thereof to strike the inclined upper wall 59 of the groove, which curved wall bends the upturned portion downwardly over the bar or finger 60. In this manner, the material of the bag or package A is bent upon itself to form a fold which closes 35 the open end of the bag.

When the device is operating, the electrical heating elements 12 which are mounted in the block B (Figure 9) are also operating, whereby the block is heated. After the bag is folded upon itself as has been explained, to close its open end, the folded portion of said bag must 40 pass through the narrow portion of the groove 57 in said block. As said bag moves through this portion of the groove, it is heated, whereby the wax is melted to some degree.

Immediately upon leaving the groove 57, the folded portion of the bag is passed between the crimping rollers 74. As has been explained, any 45 desired pressure may be applied to the folded portion and since the wax has been softened by heating the fold will be tightly pressed against the remainder of the bag, whereby said fold will adhere thereto. As soon as the folded portion passes through the crimping rollers 74, it is entered between the pressure belts 82 and 83. These belts apply a fixed pressure to the fold and, while passing between said belts, the bag is 50 permitted to cool. As the wax, which has been previously softened by the heating operation, becomes cool, it will be evident that the fold will adhere to the remainder of the bag. Thus, the fold will be firmly sealed and the open end of the bag permanently closed. As the bags pass

outwardly from between the pressure belts 82 and 83, they may be conducted to a suitable container, or otherwise disposed of.

From the foregoing, it will be seen that a simple and effective method for folding and sealing the open ends of packages is provided. The operation is a continuous one as the bags are successively passed between the various rollers to be folded, then heated, then crimped, and finally cooled under pressure. The various rollers, as has been explained, are yieldably mounted so that a proper pressure is at all times maintained to efficiently perform the various operations. A single electric motor 95 is employed for operating all of the movable parts, which makes for economy in operation. It is particularly pointed out that the method disclosed herein provides for sealing the open ends of the packages without the danger of damaging the contents of said packages. An important feature of the invention is the particular method and means for automatically folding the open end portion of the bag or package upon itself. It is this means which makes possible the closing and sealing of the packages without any manual labor or attention. It is noted that although the method has been described with the bags moving from left to right in Figures 1 and 2, it is obvious that the mechanism could be rearranged to move the bags in an opposite direction without departing from the invention.

The foregoing description of the invention is explanatory thereof and various changes in the size, shape and materials, as well as in the details of the illustrated construction, may be made, within the scope of the appended claims, without departing from the spirit of the invention.

What we claim and desire to secure by Letters Patent is:

1. An apparatus for closing and sealing packages including, a support, means for conveying a package to be closed and sealed longitudinally of said support, a folding assembly comprising a pair of rollers one of which has a peripheral flange, means for passing the end portion of the package between said rollers to cause folding of said end portion at substantially a right angle to the remainder of the package, a folding assembly block for receiving the bent portion of the package and having means for folding said portion back over the end portion of the package, and means for sealing said folded portion to the underlying portion of the package to seal the package.

2. An apparatus for closing and sealing wax coated packages including, a support, means for conveying a package to be closed and sealed longitudinally of said support, a folding assembly comprising a pair of rollers one of which has a peripheral flange, means for passing the end portion of the package between said rollers to cause folding of said end portion at substantially a right angle to the remainder of the package, a folding assembly block for receiving the bent portion of the package and having means for folding said portion back over the end portion of the package, means for heating said folded portion to soften the wax coating, and means for applying pressure to said heated portion to cause cohesion of the contacting wax surfaces.

3. An apparatus for closing and sealing wax coated packages including, a support, means for conveying a package to be closed and sealed lon-

gitudinally of said support, a folding assembly comprising a pair of rollers one of which has a peripheral flange, means for passing the end portion of the package between said rollers to cause folding of said end portion at substantially a right angle to the remainder of the package, a folding assembly block for receiving the bent portion of the package and having means for folding said portion back over the end portion of the package, means for heating said folded portion to soften the wax coating, means for applying pressure to said heated portion, and means for maintaining said folded portion under a pressure while cooling to cause cohesion of the contacting wax surfaces.

4. As a sub-combination in a package sealing apparatus, a folding assembly including, a pair of rollers having their peripheries engaging, one of said rollers having a peripheral flange abutting the side of the other roller, whereby when the outer end portion of a package is passed therebetween said end is bent at substantially a right angle to the remainder thereof, and a folding block associated with said rollers and having an opening provided with a curved wall for receiving and for folding said bent portion downwardly so as to overlie the end portion of the package.

5. As a sub-combination in a package sealing apparatus, a folding assembly including, a pair of rollers having their peripheries engaging, one of said rollers having a peripheral flange abutting the side of the other roller, whereby when the outer end portion of a package is passed therebetween said end is bent at substantially a right angle to the remainder thereof, a curved guide shoe adjacent the rollers for aiding in bending said portion, and a folding block associated with said rollers and having an opening provided with a curved wall for receiving and for folding said bent portion downwardly so as to overlie the end portion of the package.

6. An apparatus for closing and sealing bags including, a longitudinal support, a pair of endless belts adapted to receive a bag therebetween for conveying the same longitudinally of the support, a folding assembly disposed in the path through which the open end of the bag is moved by the conveyor belts, said folding assembly comprising a pair of rollers for receiving the end portion of the bag, a guide shoe adjacent the rollers and co-acting therewith for affecting a folding of said end portion of the bag at substantially a right angle to the remainder of said bag, a folding block beyond the rollers having a recess, the vertical wall of which is aligned with the face of the guide shoe so as to receive the folded end of the bag, said vertical wall being gradually curved to a horizontal plane, whereby as the end portion of the bag moves therethrough, it is bent back upon the remainder of the bag, and means beyond the block for sealing the folded end of the bag.

7. An apparatus for closing and sealing bags including, a longitudinal support, a pair of endless belts adapted to receive a bag therebetween for conveying the same longitudinally of the support, a folding assembly disposed in the path through which the open end of the bag is moved by the conveyor belts, said folding assembly comprising a pair of rollers for receiving the end portion of the bag, a guide shoe adjacent the rollers and co-acting therewith for affecting a folding of said end portion of the bag at substantially a right angle to the remainder of said bag, a folding block beyond the rollers and in the

path of the end portion of the bag, said block having a longitudinal groove in its face for receiving the folded end portion of the bag, the inlet end of said groove being enlarged and being gradually reduced with the vertical wall of the groove being gradually curved toward a horizontal plane, whereby as the bent end portion of the bag moves therethrough, the bag is folded upon itself to close the open end thereof, and means beyond the block for permanently fastening the folded end of the bag in a closed position.

8. An apparatus for closing and sealing bags including, a longitudinal support, a pair of endless belts adapted to receive a bag therebetween for conveying the same longitudinally of the support, a folding assembly disposed in the path through which the open end of the bag is moved by the conveyor belts, said folding assembly comprising a pair of rollers for receiving the end portion of the bag, a guide shoe adjacent the rollers and co-acting therewith for affecting a folding of said end portion of the bag at substantially a right angle to the remainder of said bag, a folding block beyond the rollers and in the path of the end portion of the bag, said block having a longitudinal groove in its face for receiving the folded end portion of the bag, the inlet end of said groove being enlarged and being gradually reduced with the vertical wall of the groove being gradually curved toward a horizontal plane, whereby as the bent end portion of the bag moves therethrough, the bag is folded upon itself to close the open end thereof, an elongate plate mounted within the groove and spaced from the lower end thereof with its inner longitudinal edge spaced from the vertical wall of the groove, whereby the bag moves beneath the plate while the bent end thereof passes through the space between the plate and vertical wall of the groove, such disposition of the bag causing the bent end thereof to be folded back over the plate by its contact with the curved wall, whereby the end of said bag is closed, and means beyond the block for permanently securing the fold of the bag in its closed position.

9. An apparatus for closing and sealing bags including, a longitudinal support, a pair of endless belts adapted to receive a bag therebetween for conveying the same longitudinally of the support, a folding assembly disposed in the path through which the open end of the bag is moved by the conveyor belts, said folding assembly comprising a pair of rollers for receiving the end portion of the bag, a guide shoe adjacent the rollers and co-acting therewith for affecting a folding of said end portion of the bag at substantially a right angle to the remainder of said bag, a folding block beyond the rollers and in the path of the end portion of the bag, said block having a longitudinal groove in its face for receiving the folded end portion of the bag, the inlet end of said groove being enlarged and being gradually reduced with the vertical wall of the groove being gradually curved toward a horizontal plane, whereby as the bent end portion of the bag moves therethrough, the bag is folded upon itself to close the open end thereof, heating means associated with the block for heating the bag to soften the wax coating thereon, and pressure means beyond the block for applying pressure to the heated folded end portion of the bag to affect a sealing thereof.

10. An apparatus for closing and sealing bags including, a longitudinal support, a pair of end-

less belts adapted to receive a bag therebetween for conveying the same longitudinally of the support, a folding assembly disposed in the path through which the open end of the bag is moved by the conveyor belts, said folding assembly comprising a pair of rollers for receiving the end portion of the bag, a guide shoe adjacent the rollers and co-acting therewith for affecting a folding of said end portion of the bag at substantially a right angle to the remainder of said bag, a folding block beyond the rollers and in the path of the end portion of the bag, said block having a longitudinal groove in its face for receiving the folded end portion of the bag, the inlet end of said groove being enlarged and being gradually reduced with the vertical wall of the groove being gradually curved toward a horizontal plane, whereby as the bent end portion of the bag moves therethrough, the bag is folded upon itself to close the open end thereof, heating means associated with the block for heating the bag to soften the wax coating thereon, pressure means beyond the block for applying pressure to the heated folded end portion of the bag to affect a sealing thereof, and a single prime mover mounted on the support for driving the conveyor belts, folding rollers and pressure means.

11. An apparatus for closing and sealing bags including, a longitudinal support, a pair of endless belts adapted to receive a bag therebetween for conveying the same longitudinally of the support, a folding assembly disposed in the path through which the open end of the bag is moved by the conveyor belts, said folding assembly comprising a pair of rollers for receiving the end portion of the bag, a guide shoe adjacent the rollers and co-acting therewith for affecting a folding of said end portion of the bag at substantially a right angle to the remainder of said bag, a folding block beyond the rollers and in the path of the end portion of the bag, said block having a longitudinal groove in its face for receiving the folded end portion of the bag, the inlet end of said groove being enlarged and being gradually reduced with the vertical wall of the groove being gradually curved toward a horizontal plane, whereby as the bent end portion of the bag moves therethrough, the bag is folded upon itself to close the open end thereof, an elongate plate mounted within the groove and spaced from the lower end thereof with its inner longitudinal edge spaced from the vertical wall of the groove, whereby the bag moves beneath the plate while the bent end thereof passes through the space between the plate and vertical wall of the groove, such disposition of the bag causing the bent end thereof to be folded back over the plate by its contact with the curved wall, whereby the end of said bag is closed, heating means associated with the block for heating the bag to soften the wax coating thereon, and pressure means beyond the block for applying pressure to the heated folded end portion of the bag to affect a sealing thereof.

12. An apparatus for closing and sealing bags including, a longitudinal support, a pair of endless belts adapted to receive a bag therebetween for conveying the same longitudinally of the support, a folding assembly disposed in the path through which the open end of the bag is moved by the conveyor belts, said folding assembly comprising a pair of rollers for receiving the end portion of the bag, a guide shoe adjacent the rollers and co-acting therewith for affecting a

folding of said end portion of the bag at substantially a right angle to the remainder of said bag, a folding block beyond the rollers and in the path of the end portion of the bag, said block having a longitudinal groove in its face for receiving the folded end portion of the bag, the inlet end of said groove being enlarged and being gradually reduced with the vertical wall of the groove being gradually curved toward a horizontal plane, whereby as the bent end portion of the bag moves therethrough, the bag is folded upon itself to close the open end thereof, an elongate plate mounted within the groove and spaced from the lower end thereof with its inner longitudinal edge spaced from the vertical wall of the groove, whereby the bag moves beneath the plate while the bent end thereof passes through the space between the plate and vertical wall of the groove, such disposition of the bag causing the bent end thereof to be folded back over the plate by its contact with the curved wall, whereby the end of said bag is closed, heating means associated with the block for heating the bag to soften to wax coating thereon, pressure means beyond the block for applying pressure to the heated folded end portion of the bag to affect a sealing thereof, and a single prime mover mounted on the support for driving the conveyor belts, folding rollers and pressure means.

13. An apparatus for closing and sealing bags including, a longitudinal support, a pair of endless belts adapted to receive a bag therebetween for conveying the same longitudinally of the support, a folding assembly disposed in the path through which the open end of the bag is moved by the conveyor belts, said folding assembly comprising a pair of rollers for receiving the end portion of the bag, the lowermost roller having a peripheral flange which is adjacent the peripheral portion of the side of the other roller so that the end portion of the bag passes between the flange of one roller and the face of the other roller, a guide shoe adjacent the rollers and co-acting therewith for affecting a folding of said end portion of the bag at substantially a right angle to the remainder of said bag, a folding block beyond the rollers having a recess, the vertical wall of which is aligned with the face of the guide shoe so as to receive the folded end of the bag, said vertical wall being gradually curved to a horizontal plane, whereby as the end portion of the bag moves therethrough, it is

bent back upon the remainder of the bag, and means beyond the block for sealing the folded end of the bag.

14. An apparatus for closing and sealing bags including, a longitudinal support, a pair of endless belts adapted to receive a bag therebetween for conveying the same longitudinally of the support, a folding assembly disposed in the path through which the open end of the bag is moved by the conveyor belts, the belts being round in cross-section and travelling in a path contiguous to the folding assembly so that the bags may be filled up to said belts and the folding operation does not reduce the content size of said bag, said folding assembly comprising a pair of rollers for receiving the end portion of the bag, a guide shoe adjacent the rollers and co-acting therewith for affecting a folding of said end portion of the bag at substantially a right angle to the remainder of said bag, a folding block beyond the rollers having a recess, the vertical wall of which is aligned with the face of the guide shoe so as to receive the folded end of the bag, said vertical wall being gradually curved to a horizontal plane, whereby as the end portion of the bag moves therethrough, it is bent back upon the remainder of the bag, and means beyond the block for sealing the folded end of the bag.

15. An apparatus for closing and sealing bags including, a longitudinal support, a pair of endless belts adapted to receive a bag therebetween for conveying the same longitudinally of the support, means for yieldably maintaining a pressure on the belts so as to yieldably clamp the bag therebetween, a folding assembly disposed in the path through which the open end of the bag is moved by the conveyor belts, said folding assembly comprising a pair of rollers for receiving the end portion of the bag, a guide shoe adjacent the rollers and co-acting therewith for affecting a folding of said end portion of the bag at substantially a right angle to the remainder of said bag, a folding block beyond the rollers having a recess, the vertical wall of which is aligned with the face of the guide shoe so as to receive the folded end of the bag, said vertical wall being gradually curved to a horizontal plane, whereby as the end portion of the bag moves therethrough, it is bent back upon the remainder of the bag, and means beyond the block for sealing the folded end of the bag.
